UNITED STATES PATENT OFFICE.

JOHN L. CABELL, OF SAVANNAH, GEORGIA.

SPECIAL RECEPTACLE.

1,155,791.

Specification of Letters Patent.

Patented Oct. 5, 1915.

Application filed July 25, 1914. Serial No. 853,158.

To all whom it may concern:

Be it known that I, JOHN L. CABELL, a citizen of the United States, residing at Savannah, in the county of Chatham and State of Georgia, have invented certain new and useful Improvements in Special Receptacles; and I do hereby declare the following to be a full, clear, and exact description of the invention, such as will enable others skilled in the art to which it appertains to make and use the same.

This invention comprehends certain new and useful improvements in special receptacles, and has for its primary object to provide a device of this character which will be of extremely simple construction and operation as well as cheap to manufacture and highly efficient in use.

Another object of the invention is to provide a device of this character which will be especially adapted for holding sticks of chewing gum and similar articles and presenting a new article to position for removal upon the removal of the uppermost article.

The invention has for another object to provide a special receptacle of this character including an inner box adapted for sliding movement in a case and provided with a false bottom and means for resiliently forcing said false bottom upwardly to press the uppermost article placed upon said false bottom against the top of the casing, at one end of which is provided a cutaway portion whereby the uppermost article may be readily grasped and extracted when the inner box is pressed inwardly against a spring provided for resiliently retaining said box in normal position within said casing.

The invention has for a further object to generally improve and simplify the construction and operation of devices of this character and increase the efficiency thereof without materially increasing the cost of the same.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which—

Figure 1 is a perspective view of the complete device in use, Fig. 2 is a vertical longitudinal section through the same, and Fig. 3 is a horizontal longitudinal section through the device on the plane of line 3—3 of Fig. 60 2, looking in the direction indicated by the arrow.

Referring in detail to the drawings by numerals, 1 designates the outer casing which has one end closed, as shown at 2, while the 65 opposite end of said outer casing is open, a stop shoulder 3 being positioned in the closed end of the outer casing 1, at the upper portion thereof and extending transversely of said outer casing to prevent the uppermost article 4 resting upon the false bottom 5 from moving rearwardly in the outer casing 1 upon inward movement of the sliding box 6 within which said false bottom is positioned and resiliently forced upwardly by 70 means of a pair of leaf springs 7 which have their outer or lower ends secured to the solid bottom of said sliding box 6, while their opposite ends are provided with elongated longitudinal slots 8 through which the guide 75 pins 9 are extended and secured in said false bottom 5.

The top of the outer casing 1 is preferably provided with an opening 10 of oval form within which is positioned a transparent 85 member 11, whereby the contents of the device may be readily seen, and it will be understood that while this device is especially adapted for holding a number of sticks of chewing gum and automatically feeding the 90 same into position to be extracted therefrom tickets and other similarly shaped articles may be placed in the device also.

It will also be understood that the outer casing 1 is provided at its open end with finger openings 12 in its top and bottom by cutting away portions of said top and bottom at the forward or open end of the outer casing, whereby the uppermost article may be readily grasped and withdrawn when the 100 box 6 is forced inwardly against the tension of leaf spring 13 which is secured to the inner face of the closed end 2 of the outer casing 1 and has its opposite free ends bearing against the inner end 14 of the sliding box 6 105 to resiliently retain said box in normal position with its outer end 15 about flush with the outer open end of the outer casing 1.

It will be readily seen that the finger opening 12 will also permit the operator to 110

readily withdraw the sliding box 6 for the purpose of refilling or repairing the same. It will be further noticed that I have cut away the upper corners of the sides of the 5 sliding box 6, while the main portions of said sides are extended into the position adjacent the inner face of the outer casing 1. This will permit the rear end of the inner 10 sliding casing 6 to slide beneath the stop shoulder 3 and cause the uppermost article upon the false bottom 5 to be forced outwardly and at the same time prevent upward movement of the inner sliding box 6 when the same is empty or practically empty 15 and make it impossible for the sliding box to slide over the outer casing 1.

Longitudinal movement of the inner sliding box 6 within the outer casing 1 is limited by the guide lug 16, at the bottom of 20 the inner sliding box 6 and engaging the guide channel 17 formed in the upper face of the bottom of the outer casing 1, and extending for a short distance longitudinally 25 of the same. It will be evident, however, that the inner sliding box may be readily withdrawn by pressing the opposite sides of the outer casing 1 to bulge the bottom thereof slightly and thereby disengage the lugs 16 from the guide groove 17.

30 While I have shown and described the preferred embodiment of my invention, it

will be understood that minor changes in the details of construction, combination, and arrangement of parts may be made without departing from the spirit and scope of the 35 invention as claimed or sacrificing any of the advantages thereof.

What is claimed is:—

A receptacle of the character set forth, 40 comprising a card box having an open upper side, a spring pressed follower mounted in the box and acting to expel the cards upwardly therefrom, a casing for the box, said casing having an open end and a recess in its top wall at said end, the casing being deeper 45 than the box so as to permit a card being pressed against said top wall at a point above the box, a shoulder located at the rear end of the casing above the box and engaging the inner end of said card, and the 50 casing being longer than the holder so that an inward movement of the latter will dispose its front wall inwardly beyond the open end of the casing and the front end of 55 said ticket, and a spring maintaining the holder in normal position.

In testimony whereof I affix my signature in presence of two witnesses.

JOHN L. CABELL.

Witnesses:

JOSEPH H. COMER,
T. H. BELL.
